G. AUSDAL

DOOR LATCH

Filed May 10, 1924

Patented Jan. 19, 1926.

1,570,195

UNITED STATES PATENT OFFICE.

GEORGE AUSDAL, OF MARSHALLTOWN, IOWA.

DOOR LATCH.

Application filed May 10, 1924. Serial No. 712,333.

To all whom it may concern:

Be it known that I, GEORGE AUSDAL, a citizen of the United States, residing at Marshalltown, in the county of Marshall and State of Iowa, have invented certain new and useful Improvements in Door Latches, of which the following is a specification, reference being had to the accompanying drawings.

10 This invention relates to improvements in door latches, and particularly to those door latches which are mounted upon the base-board or otherwise adjacent the floor and which project out therefrom and which are 15 adapted to engage the door as it is swung open so as to hold the door open until the latch is released, these latches being released by the foot.

One of the objects of the invention is to 20 provide a latch of this character which is very simple, which may be cheaply constructed, and which is thoroughly effective.

A further object is to provide a construction of this character so formed that one 25 bolt holds the latch and the casing together.

A still further object is to provide a latch 30 of this description which may be used on doors that open either to the right or to the left without changing anything in the latch 35 itself.

Another object is to provide means whereby the latch may be operated from either side and in which the latch is operated by gravity and not by a spring, and in which 40 the device may be operated by the toe of the shoe.

Other objects will appear in the course of the following description.

My invention is illustrated in the accompanying drawings, wherein:

Figure 1 is a perspective view of a latch constructed in accordance with my invention:

Figure 2 is a vertical sectional view of a portion of a mop board with my latch applied and a coating portion of the door with the keeper;

Figure 3 is a perspective view of the latch detached from its casing;

Figure 4 is a perspective view of the keeper detached from the door.

Referring to these drawings, it will be seen that the casing of the latch is formed in two sections A and B and that the section A is formed of a single casting providing a face plate 10, a side wall 11, the end walls 12, and

the wall 13 which extends parallel to the wall 11. The wall 11 extends beyond the end walls 12 and the upper end of this end wall is rounded and formed with a countersunk screw aperture 14. The lower end of this end wall is also formed with a screw aperture 14 and thus the casing may be attached to the mop board or base-board of the wall.

The wall 11 is preferably formed with a recess 15 and the wall 13 is formed with a like recess 15, but this recess is intersected by a latch opening 16. The end walls are each formed with a pair of recesses 17 at the junction of the end walls with the side walls. The face plate 10 is formed with an aperture for the passage of a bolt 18, and oscillatably mounted upon this screw is the latch 19. This latch is formed of a single casting having a relatively large butt end through which the bolt 18 passes, and the latch is reduced so as to pass through the opening 16 and at its outer end is formed with a latching head 20, this latching head having a straight inner face and an inclined outer face. Inward of this latching head and, therefore, inward of the wall 13 the latch is formed with an integral weight 21 and through this latching weight extends the pin 22.

The plate 10 is formed with an arcuate slot 23 through which the pin passes, and the section B is also formed with a corresponding arcuate slot 24 through which the other end of the pin passes. Thus the pin projects out through the sections A and B on each side thereof so that the latch may be manipulated from either side. The section B is adapted to rest against the section A and be complementary thereto. This section B is formed of a plate of metal and recessed at its ends, as at 25, and at its side edges adjacent its ends the plate is recessed, as at 26, so that this plate fits into the recesses 15 and 17 of the side and end walls.

The bolt 18 passes through an aperture in the section B and by means of this bolt the plate or section B is held upon the casing A, the interlocking tongues and recesses formed upon the edges of the plate or section B and the edges of the walls of the section A preventing any rotative movement of the plate B after the nut on the bolt 18 has been turned home.

This latch is intended to be mounted upon the mop board C of the floor by means of screws passing through the apertures 14, as illustrated in Figure 2, and the door is pro-

vided with a keeper plate 27, this plate being provided with screw openings 28 whereby it may be attached to the door and provided with a central square opening 29 through which the head of the latch 20 is adapted to project when the door is in engagement with the latch. The door is to be recessed behind the opening 29 in the plate 27 so as to permit the projection of the head 10 of the latch into the opening 29 and the engagement of this latch head with the margins of the plate, the plate being adapted to lift the latch as the door is swung to a closed position.

15 The use of this device will be obvious from what has gone before. The latch casting is mounted upon the mop board with the latch swung outward, and when the door is swung fully open the latch will engage the 20 door. It will be seen that there is nothing projecting from the door which can possibly form an obstruction or which can catch on clothes or on any object passing through the door, and when the door is 25 opened the latch is entirely covered by the door itself so that there is no possible obstruction to passing through the door in either direction. This latch is particularly designed for house doors, garage doors and 30 large heavy factory doors, and it will be obvious that this latch without any change

can be used either on doors that open to the right or those that open to the left, for the reason that the pin 22 projects in opposite directions through the latch casing. The 35 door may be readily released by the toe of the shoe without bending over.

I claim:—

A latch of the character described comprising a casing formed to provide a section 40 having a face plate and side and end walls, the end and side walls being recessed on their edges and one of the side walls being extended beyond the end walls and being apertured for the passage of screws, the 45 opposite side walls having an aperture for the passage of a latch, the other section comprising a plate adapted to rest against the side and end walls of the first section and being recessed complementarily to the 50 recesses on the side and end walls, a single screw passing through said plate and through the opposite face plate and through the latch and acting to pivotally support the latch and hold the two sections of the casing 55 together, and a pin extending through the latch and through the plates of the two sections, the plates having arcuate slots through which the pin passes.

In testimony whereof I hereunto affix my 60 signature.

GEORGE AUSDAL.
